A. I. Root Company, Medina, Ohio, a corpora-
tion of Ohio

Application June 9, 1932, Serial No. 616,281

4 Claims. (Cl. 67—21)

This invention is a modification of the invention disclosed in my prior application Serial Number 494,459, filed November 10, 1930, (Patent 1,867,420, reissued October 18, 1932 as Re. 5 18,623) and this application is, in part, a continuation of said prior application.

In my prior application, there are shown two types of devotional or sacramental lights employing a solid fuel body and translucent or 10 transparent casing for the fuel body, which casing substantially fits the body. The latter in the preferred type, is shaped by the casing walls, being solidified in place from a molten state. The other illustrated type is one in 15 which the fuel body is formed or cast separately from the casing and later placed therein for consumption by lighting a suitable wick contained in the body. The present case relates to the latter type. An essential improvement 20 over prior arrangements represented by both types is a restricted opening at the top of the casing which retains heat from the flame, conducts this heat to the fuel body—which is substantially in close contact with the vertical or 25 side surfaces of the fuel body—, thereby maintaining the walls of the casing free from congealed fuel opposite the flame at all times, and, moreover, has been found to restrict the entrance of air to the flame to such an extent 30 that the flame is maintained relatively small and smokeless.

The fuel body (actually a candle) may extend into close fitting contact with the restricted portion of the casing with beneficial results, as 35 pointed out and claimed in my prior case, or this body may initially lie below the restricted portion. In the latter event, lighting the wick is difficult and one of the objects of the present invention is to provide for more easily lighting 40 such candle.

Another object is to provide a removable restriction affording casing section for a light of the character shown in my copending case, which section is maintained in full heat conducting contact with an adjacent section, but which is also so arranged that there will be no danger of fracture of either section when 45 unequally heated or cooled by the operation of the light.

It is sometimes desirable to make the casing with one or both ends entirely open to facilitate 50 cleaning, particularly where the casing is entirely exposed, that is, used without any surrounding housing, such as a conventional "ruby" glass or cylinder. An object is to provide a cas-

ing for such purpose which may be easily cleaned, notwithstanding that the fuel is maintained in close contact with the casing during substantially the entire burning period.

Where the casing is open at the bottom, I 5 discovered in my early experiments that leakage of melted fuel often resulted at or near the end of the burning period, notwithstanding the use of what would seem to be very effective sealing means at the bottom. In line with the 10 above, an object is to provide for containing and supporting the lower end of such casing in such manner that leakage of melted fuel does no harm. In other words, if leakage results, it does not reach the visibly exposed surfaces of 15 the base of the light and thereby become unsightly or spill out onto the surface supporting the light.

Other objects and features of the invention 20 will become apparent from the following description relating to the accompanying drawing, showing the preferred forms. The essential characteristics are summarized in the claims.

In the drawing, Fig. 1 is a central sectional view of one form of light suitable as a "sanctuary" light; Fig. 2 is a similar view showing the lower portion of the light near the end of the burning period; Fig. 3 is a sectional view showing particularly a modified joint between two portions of the casing, and Fig. 4 is a sectional view showing a preferred wick holder particularly for a casing with a closed bottom.

Referring first to Fig. 1, this shows a suitable translucent or transparent main casing member at 1, preferably glass, housing the fuel body 35 A having a suitable wick B. The member 1, as shown, comprises a cylinder open at both ends. If there is no surrounding casing ("ruby cylinder", e. g.) in addition to the casing member 1, then this casing member may be made of 40 suitably colored glass (usually red). Surmounting the member 1 is an annular member 2 of suitable material, such as glass similarly colored if desired, and preferably translucent or transparent. This is generally dome shaped and has a restricted opening at 3 considerably smaller than the inner diameter of the casing member 1. The two parts 1 and 2 are connected by a suitable joint, permitting easy detachment, and 45 preferably the joint provides at least one definite abutment surface, such as at 4, and also mutually telescoping surfaces as at 5 for adequate heat conductive contact between the two. The telescoping surfaces are preferably at 50 least slightly conical.

The upper end of the casing member 1, as shown in Fig. 1, is brought in slightly at 6 from the general diameter of the casing member, reinforcing the rim and providing the shouldered joint just described. With this arrangement, the joint will be inconspicuous on the outside surface of the casing.

Fig. 3 shows another arrangement of joint. Here the heat conducting contact between the parts 1 and 2 is afforded by definite complementary conical surface at 7, but sloped or beveled at such an angle that upon expansion of one member with reference to the other (as when heated), the expanded member may move freely radially or axially relative to the other. The part 2, as shown in Fig. 3, when expanded by heat as the candle starts burning, will merely rise a very slight distance, later settling back but always preserving full contact.

It may be noted that the slight flange 8 at the bottom of the member 2, as illustrated in Fig. 3, provides a suitable shoulder for supporting the usual reticulated insect guard (not shown) which is ordinarily used to cover the opening at the top of devotional lights of the type shown. Moreover, if the lower end of the casing member 1 is closed in the manner illustrated in Fig. 4, then the entire light (with no base) may be very easily suspended, say by a suitable ring embracing the casing 1 below the flange effect 9 at the top of the latter, and suitable chains attached to the ring.

The telescoping joint between the members 1 and 2 may be loose enough to take care of unequal expansion, but this cuts down the desired conductivity of heat from one member to the other at the start.

The casing member 1 is shown as entirely open at the bottom, allowing the candle to be slid through the open end into the position illustrated. It is obvious that with the open bottom end, the casing 1-2 may be made all in one piece, more in accordance with my copending application.

At the base of the casing member 1 and embracing a portion of the latter, there is an imperforate cup 10, preferably formed in one piece, the side wall 11 of this cup extending above the normal maximum depth of melted fuel at or near the end of the burning period of the candle (see Fig. 2). This cup may be metal, but in order not to obstruct light from the burning wick near the end of the burning period, the cup is preferably translucent. It may be made of glass or other transparent or translucent non-inflammable composition.

I have observed that, during some temperature conditions, the fuel melts between the still solid fuel body and the inside surface of the casing for a considerable distance down from the melted fuel pool at the top of this solid fuel body. At some intermediate stage in the burning period, it is manifest that this may cause melted fuel to seep out from under the lower edges of the casing 1 into the cup. By enlarging the cup at the base, adequate space may be provided as at 11x, which will collect such slight seepage, preventing an overflow, notwithstanding that the level of the pool of melted fuel is still well above the brim of the cup. Fuel seeping into the cup at the stage just mentioned is solidified in the annular space 11x probably both because of loss of heat by convection, due to the fact that the space 11x is not closed at the top and loss of heat from the lower portions

of the casing part 1, fuel body etc. by conduction of heat to the wall 11, and radiation therefrom into the outside air. An inch and one-half high wall on the cup is adequate at maximum expected temperatures. The wall may be higher, and if transparent or adequately translucent for the light to show through the wall may be several inches high with no disadvantageous effects. The depth of melted fuel illustrated in Fig. 2 is, incidentally, an exaggerated condition. Ordinarily, the depth is no more than an inch in a casing measuring three inches, outside diameter. With a larger casing, the depth at the same temperature would be less.

The parts above described, including the candle may be suitably supported as by a conventional base indicated in broken lines at 12, which, as shown, has a flange embracing the lower portion of the cup and which underlies the cup to support it.

The fuel body and wick, as above mentioned, may comprise a suitable candle, preferably of such size as to substantially fit the casing member 1. As shown, the fuel body lies wholly within the cylindrical portion of the casing but, it may, instead, extend upwardly into the restriction affording member 2 in close contact with or spaced therefrom as desired.

At the lower end of the wick and embedded in the fuel body is a preferred wick support. This comprises a small block of wood 15, apertured as at 16 to receive the wick and suitably weighted so that it will not float in the melted fuel. The weight, as shown, comprises a strip of sheet metal 17 having an opening therethrough to receive a reduced portion 15a of the block which extends upwardly through the opening into the fuel body. This upwardly projecting portion of the block burns for a time when exposed above the level of melted fuel and lengthens the burning considerably while still supporting the wick in upright position. The bottom of the cup 10 slopes inwardly in the form shown and substantially all the fuel, including any that may have seeped into the space 11x, is consumed, the heat near the end of the burning period being adequate to maintain such fuel as may be caught in the outer portions of the cup melted.

A modification of the wick support is shown in Fig. 4, wherein the ends of the metal strip 19 are shown as bent down at 19a into contact with the outer bottom surfaces of the main casing member 1' (shown as closed at the bottom in this figure,—conventional glass jar or bottle construction. It will be understood that the arrangement shown in Fig. 3 may have an inwardly turned reinforcing rib as indicated at 20, which, while it precludes inserting the candle from the bottom, supports the candle in such manner that the latter may be picked up with the casing. Moreover, the novel characteristics of the detachable top section of the casing may, of course, be used with a casing, the bottom of which is closed in the manner of an ordinary glass jar (according to the disclosures of my prior application, e. g.).

It will be seen that with the device of the proportions shown, as soon as the flame is burning the walls of the casing which are adjacent the outer candle surfaces, are heated by the conductivity of heat from the inwardly overhanging portion of the casing (part 2, as shown). As the candle burns down, the side walls of the casing are further heated by direct

radiation from the flame. A pool of melted fuel extending entirely across the casing is formed in an hour or less after lighting, and the pool is retained by the casing walls. The 5 heated walls of the casing prevent the fuel from congealing and forming an opaque ring on the wall opposite the candle flame, obstructing the light of the flame. Moreover, the restricted opening at 3 reduces the volume of air admitted 10 to the candle flame and thus causes the flame to burn relatively low, thus lengthening the burning period. The features and advantages mentioned in this paragraph are all present in the arrangements of my prior application.

15 Where the candle is initially below the top edges of the cylindrical portions of the casing as in the present arrangement illustrated, it will be seen that the matter of lighting the wick is facilitated, as it is only necessary to remove the 20 top section 2 and replace after lighting to avoid all danger of damage to the glass by the lighter flame.

The casing being entirely open at one end (or both ends) permits easy cleaning, notwithstanding that some fuel and carbon is inevitably left on the walls. The removable section 2 of the casing collects the residue which is most difficult to clean off and the separability of the part 2 from the main portion of the casing is 30 thus an advantage in cleaning both parts.

The advantages on the deep bottom closure cup, the wick support herein shown, and other distinctive features disclosed in this and not in the prior application, are believed clear from 35 the above description.

Having thus described my invention, I claim:

1. A light of the class described comprising an elongated translucent glass casing open at the top, a fuel body and suitable flame supporting wick within the casing, said fuel body being substantially transversely coextensive with said casing and substantially filling the same vertically, a glass hood detachably and snugly telescopingly engaging the upper marginal wall 45 of said casing by glass to glass contact therewith and forming substantially a continuation of the casing wall for conducting the initial heat of the flame to the casing, said hood being in intimate heating relationship to the flame during initial burning thereof and having a central opening for admitting air to and discharging hot gases from the flame of the wick, and means 50 for compensating for expansion of the hood relative to the casing consequent upon initial heating of the hood by the flame, whereby danger of breaking the casing and hood is minimized.

2. A light of the class described, comprising a translucent hollow casing open at the top, a solid fuel candle contained in the casing in 55 close proximity to the inside surfaces thereof throughout substantially the length of the

candle, and a removable annular member surrounding the casing in overhanging relation to the candle and in substantially closely surrounding relation to the flame of the wick thereof when the wick is first lighted, said annular member having a restricted opening above the candle for admitting air and discharging hot gases, said annular member having a beveled lower surface of greater width than the thickness of said member and the casing having an adjacent substantially complementarily beveled upper surface contacting therewith for the full width thereof, whereby more effective heat conducting contact between the annular member and casing will be maintained and whereby the annular member and casing may move relatively during unequal contraction and expansion.

3. A light of the class described comprising a hollow translucent casing, an elongated solid fuel candle body disposed within the casing in such proximity to the wall thereof throughout substantially the entire length of the body that the casing retains a pool of melted fuel material on top of the remaining solid fuel during the burning thereof, the casing being open at the bottom, and a cup device telescopingly receiving said open bottom end portion of the casing and having an imperforate wall extending upwardly exteriorly of the lower margin of the casing wall and terminating upwardly close to the level defined by the level of the fuel in the casing when all the remaining fuel in the casing has reached a molten condition as a result of the heat of the flame of the light under surrounding conditions in which the light is utilized, whereby the melted fuel will be prevented from escaping and flowing onto surfaces on which the light may be supported.

4. A light of the class described comprising an elongated hollow translucent casing, a solid fuel candle body disposed within the casing in such proximity to the wall thereof throughout substantially the entire length of the body that the casing retains a pool of melted fuel material on top of the remaining solid fuel during burning thereof, the casing being open at the bottom, and a cup device telescoping said open bottom end and having a translucent imperforate wall extending upwardly exteriorly of the lower margin of the casing wall to a height sufficient to 40 prevent overflow of the cup device at a time when all the remaining fuel in the casing is in a molten state, whereby melted fuel will be prevented from flowing to surfaces on which the light may be supported and whereby the flame 45 of the candle will be visible from a point of view horizontally opposite the imperforate wall when the flame is below the upper edge of said imperforate wall.

HUBER H. ROOT.
